(57) **CLAIM**

The ornamental design for a line crimp apparatus, including as shown and described.

DESCRIPTION

FIG. 1 depicts a front perspective view of the line crimp apparatus of the present invention.

FIG. 2 depicts a top view of the line crimp apparatus depicted in FIG. 1.

FIG. 3 depicts a bottom view of the line crimp apparatus depicted in FIGS. 1 and 2.

FIG. 4 depicts a first side elevation view of the line crimp apparatus depicted in FIGS. 1 through 3.

FIG. 5 depicts a second side elevation view of the line crimp apparatus depicted in FIGS. 1 through 4, rotated about a substantially vertical axis compared to the view depicted in FIG. 4.

FIG. 6 depicts a front elevation view of the line crimp apparatus depicted in FIGS. 1 through 5.

FIG. 7 depicts a rear elevation view of the line crimp apparatus depicted in FIGS. 1 through 6, rotated about a substantially horizontal axis compared to the view depicted in FIG. 6; and,

FIG. 8 depicts a detailed perspective view of line crimp apparatus depicted in FIGS. 1 through 7.

The broken lines in FIG. 8 depict environmental structure and form no part of the claimed design.
